UNITED STATES PATENT OFFICE.

ROSCOE M. ST. JOHN, OF ALBANY, INDIANA, ASSIGNOR OF ONE-HALF TO
LEWIS R. ST. JOHN, OF SAME PLACE.

POST-DRIVER.

SPECIFICATION forming part of Letters Patent No. 274,989, dated April 3, 1883.

Application filed October 10, 1882. (No model.)

To all whom it may concern:

Be it known that I, ROSCOE M. ST. JOHN, a citizen of the United States, residing at Albany, in the county of Delaware and State of Indiana, have invented a new and useful Post-
Driver, of which the following is a specification.

My invention relates to improvements in post-drivers; and the objects of my improvements are, first, to construct a cheap, simple, and durable post-driver, to be moved about on the running-gear of an ordinary wagon, and to be operated by one person. I attain these objects by the mechanism illustrated by the accompanying drawings, in which—

Figure 1 is a perspective view of my invention as ready for use, and Fig. 2 is a view of the top portion of the same.

Similar letters and figures refer to similar parts throughout the several views.

The frame D of my invention is so constructed as to be placed upon the ordinary wagon, the cross-bars *o* being made to fit in between the standards. To the rear end of the frame D are secured the blocks A' B', forming a hinge for the lower part of the posts *c c'*. The said blocks are pivoted to the frame D, so as to allow the posts *c c'* to be inclined backward or forward, as desired, a strap of iron, *s'*, being used for a hinge, as the under sides of the blocks are rounded, as shown in Fig. 1. The upper portions of the blocks A' B' are provided with a tenon, so as to fit in the slots cut in the lower parts of the blocks A B, as shown in Fig. 1, by the pins or bolts *s s'*. The blocks A B and A' B' are made to form a hinge for the "lateral" inclination of the aforesaid posts, so that they may be made to stand perpendicular independent of the position of base D. The ratchet-bar *g* and lever *g'* are secured to the block B, as shown, so that the cogs in the lever *g'* are made to engage with similar cogs in the lower end of the post *c*. Just above the blocks A B are the slack winches *f*. They are provided with two small rollers, *f' f''*, to which are secured one end of the ropes *m' m'' m'''*. The said ropes pass over the pulleys 2 and 3 at the top of the tower, then down under the pulleys 4 and 5, and then wind around the roller *t*, as shown. The rope *m* also winds around the said roller

t, and is secured to the top of the tower, as shown. The rollers *t' t* are secured on the top of the frame F, as shown, the roller *t* having a double ratchet-wheel, *i'*, and pawls *i i''*, so as to stop it, when desired, from turning either way. The roller *t'* is for the purpose of elevating the weight *b*, the rope *m'* being firmly secured to and winding around it, then passing down under the pulley 6, then up over pulley 1, and down to the trip-block *a*, to which it is attached, the block *a* being made to slide up and down between the posts *c c'*, which are firmly held together by the incline board *c''*.

The lever *a''* is attached to the block *a* by a staple, *e*. The lever is connected at its lower end to the hook *a'*, which is hinged to the under side of the block *a*, the said hook being pressed outward at the top by the spring *a'''*, as shown in Fig. 2. When the block *a* falls down on the weight *b*, the hook *a'* springs into the staple *b'* and holds the weight secure until the lever is pressed in at the top by being drawn to the top of the tower against the incline board *c''*, which pulls the hook out of the staple and allows the weight to drop independently upon the post to be driven.

When posts are to be driven in unlevel ground, the tower *c c'* may be made to stand perpendicular by adjusting it "backward" or "forward" by turning the roller *t*.

When a post is to be driven it is placed in between the blocks A' B', so that the weight *b* will strike centrally upon it. Then take hold of the crank *n'* and wind the weight up until the lever *a''* strikes the incline board and trips the hook so the weight will drop upon the post. Then let go of the crank, and the trip-block will drop down on the weight, thereby attaching in the staple *b'*, and they are ready to be raised again, as before.

Having thus described my invention, I claim—

1. In a post-driver, the weight *b*, staple *b'*, hook *a'*, rod *c'*, lever *a''*, staple *e*, spring *a'''*, and block *a*, all for the purpose set forth.
2. The tower *c c' c''*, blocks A B A' B', the winches *f* and pulleys *f' f''*, lever *g'*, and bar *g*, all for the purpose set forth.
3. The frame D, frame F, rollers *t t'*, ratchet *i i''*, ropes *m m' m'' m'''*, and pul-

leys 1, 2, 3, 4, 5, and 6, all for the purpose set forth.

4. The frame D, having the arms E E, pulleys 4 and 5, straps s', and bars o o, in combination with the frame F, rollers t t', and the ropes m m' m'' m'''.

5. The rope m, in combination with the parts a a' a'' a''' b b' e e' and tower c c' c'', for the purpose set forth.

6. The combination of the blocks A B A' B',

straps s', and pins s, with the tower c c' c'' and base D.

7. The combination of the winches f and pulleys f' f'' with the ropes m'' m''', pulleys 2 3 4 5, roller t, ratchet and pawls i i' i'', and crank n, all for the purpose set forth.

ROSCOE MORTON ST. JOHN.
